UNITED STATES PATENT OFFICE.

LOUIS KUH, OF SAN FRANCISCO, CALIFORNIA.

DESIGN FOR A CHILD'S GARMENT.

60,958.

Specification for Design.

Patented May 16, 1922.

Application filed March 14, 1921. Serial No. 452,323. Term of patent 14 years.

To all whom it may concern:

Be it known that I, LOUIS KUH, a citizen of the United States, residing at San Francisco, in the county of San Francisco and State of California, have invented a new, original, and ornamental Design for a Child's Garment, of which the following is a specification.

Fig. 2 is a back view of a child's romper showing my design.

I claim:

The ornamental design for a child's garment as shown.

LOUIS KUH.
